UNITED STATES PATENT OFFICE

RALPH HUNTER, OF NEW YORK, N. Y., ASSIGNOR TO HALL, HARTWELL & CO. INC., OF TROY, NEW YORK, A CORPORATION OF NEW YORK

ATTACHED COLLAR AND METHOD OF MAKING SAME

Application filed January 10, 1928. Serial No. 245,753.

The present invention relates to collars, and more particularly to collars of the soft "shirt-attached" type.

One objection to attached collars, notwithstanding their popularity, has been their tendency to shrink when laundered, with the result that a shirt having an attached collar, after being laundered a few times, is often useless because the size of the neckband is reduced by shrinkage.

In the manufacture of attached collars, the usual procedure has been to manufacture the collars over-size, and as an additional safeguard, to recommend the purchase of a shirt having a collar at least a half-size larger than one is accustomed to wear, so that after laundering, the collar will be of approximately the proper size.

This is objectionable, however, for the reason that when first worn, the collar is unsightly because of its excessive size, and for the additional reason that very frequently the necessity for purchasing a larger size than is ordinarily required in a detached collar, is overlooked.

An object of the present invention is to provide an improved attached collar which will be substantially shrinkage-proof because of the method employed in its manufacture, and which therefore need not be manufactured in over-sizes or purchased in larger sizes than needed in order to make allowance for shrinkage.

A further object of the invention is to provide an improved attached collar in which the band and fold-over top are made up of a plurality of separately cut plies of fabric, preferably three or more, but have the appearance of a collar made of a single-ply fabric, or a multiple ply inter-woven fabric.

A still further object of the invention is to provide an improved method of making an attached collar which will facilitate its attachment to the shirt, and which when applied, will be inherently capable in a substantially unstarched condition of receiving and maintaining a curvilinear state.

I am aware of the fact that it is customary in the manufacture of detached collars to subject the same to a laundering which neces-

sarily results in shrinkage, and I am further aware that some manufacturers subject the entire shirt and attached collar to a laundering process for the purpose of minimizing shrinkage after the purchase. This expedient has not been generally resorted to, however, for various reasons such as the expense, and the likelihood of destroying the finish and lustre of the shirt fabrics particularly of mercerized fabrics.

Notwithstanding these practices, however, to my knowledge no one has suggested or considered it practicable in the manufacture of attached collars to subject the same to a laundering shrinkage during the manufacturing process and before the collar is attached to the shirt. This practice has been considered impracticable for numerous reasons, among these being (1) the difficulty of laundering or shrinking the collar with raw exposed edges, such as are necessarily present in a collar of the "attached" type which has not been sewn to the shirt; (2) the difficulty of laundering or shrinking a partially complete collar in view of the possible variable shrinkage of its different plies, and the consequent difficulty in attaching the same after a variable shrinkage of its different plies, which also may result in a mis-shapen collar; and (3) the danger of discoloring the collar material, producing therein a different appearance than that of the shirt material.

These and other objections have forced manufacturers generally to resort to the expedients heretofore mentioned, namely, of manufacturing attached collars oversize, and of endeavoring to teach the users to purchase larger sizes than required in the detached collars.

Although the invention in its broader aspects is not limited to a collar of any particular construction, it preferably has to do with a collar, which in construction, is similar to that disclosed in my Patent No. 1,642,858, granted Sept. 20, 1927, in connection with the manufacture of which the present invention has been extensively employed.

In carrying out the method, the materials from which the collar is formed are first tested with a great deal of care to determine

with substantial exactness their action when laundered, and, more particularly, to determine their coefficient of shrinkage. In other words, instead of ascertaining merely the fact that one fabric shrinks more than the other, substantially the exact or metric relation between their shrinkages is determined by comparative tests.

After the action of the materials when laundered has been determined, the collar is formed, preferably both as to its band and fold-over top, of a plurality of plies, usually three plies, including an intermediate stiffening ply and two outer plies. This construction is used not only in the fold-over top, but also in the band, and for an intermediate ply a material having a lower coefficient of shrinkage than the outer plies is employed. Moreover, it is preferred that both the band and top shall be of corresponding construction i. e. their interliners have substantially the same coefficients of shrinkage and the outer plies have the same shrinkage coefficients, and, as to the outer plies, identity of weight and appearance is also preferred. In selecting these materials, it will ordinarily be practicable to employ for an intermediate stiffening ply, what is known as commercially shrunk fabric, and for the outer plies, commercially unshrunk fabric, although the coefficient of shrinkage of each material, as above described, should be accurately predetermined. Under laundering treatment, the outer plies will, when selected from material having the proper degree of shrinkage as compared to the interlining or intermediate ply, shrink closely and be tensioned upon the inner stiffening ply or interliner, and form a fold-over top in which the outer plies constitute in appearance the surfaces of a multiple ply interwoven fabric, although they are separate and distinct plies so far as the weaving is concerned. At the same time, in the band this result will take place and the precaution of selecting materials having proper relative coefficients of shrinkage will prevent mis-shaping and maintain the parts in their proper relative position, by causing a uniform shrinkage throughout both the top and band. With some materials it is possible to obtain satisfactory results in the subsequent shrinking process if all of the plies are of unshrunk material and, in other instances, if all of the plies are of shrunk material.

In carrying out the shrinkage process, particular care is exercised to avoid discoloring of the fabric, and such mis-shaping as would render the subsequent attachment of the collar to a shirt somewhat difficult. Preferably, the collars are shrunk in substantially flat condition, and thereafter thoroughly dried. Collars made of certain fabrics after the drying step are dampened, and thereafter left to stand or age for an extended period,

preferably at least twelve hours. After the drying period, the collars made of these fabrics are given a preliminary ironing. Thereafter, along with collars which may be attached to the shirt after the drying operation, they are attached to the shirt in the manner to be later described, and the final collar ironing is thereafter given, particular care being exercised to iron in such a manner and to leave the collar material substantially the same in appearance as that of the shirt.

In addition to the method which has been above outlined, the invention also relates to the collar construction, and this phase of the invention, together with the method, will be more clearly understood as the description proceeds in connection with the explanation of the preferred embodiment of the collar which is shown in the accompanying drawings, wherein:

Figure 1 is a perspective of the fold-over top partially completed.

Figure 2 is a cross-sectional view on the line 2—2 of Figure 1.

Figure 3 is a perspective of the fold-over top completed, and ready for attachment to the band.

Figure 4 is a cross-sectional view on the line 4—4 of Figure 3.

Figure 5 is a perspective view showing the first step in attaching the band and fold-over top.

Figure 6 is a view showing the band partially folded down after its attachment to the top.

Figure 7 is a cross-sectional view on the line 7—7 of Figure 6.

Figure 8 is a perspective view showing the completed collar ready for the shrinkage process.

Figure 9 is a fragmentary perspective view showing the collar partially attached to the shirt.

Figure 8 is a perspective view showing the collar completely attached to the shirt.

The fold-over top of the collar comprises at least three plies, namely, an interlining ply 10 of comparatively heavy fabric flatly interposed between two outer plies 11 and 12. The interlining ply is formed from material having a relatively lower coefficient of shrinkage than the outer plies 11 and 12. Ordinarily, the interliner will be formed of what is known as commercially shrunk fabric, and the outer plies of commercially unshrunk fabric, although in some instances all of the plies may be of "unshrunk" material and in other instances all of the plies of "shrunk" material which, of course, will have some shrinkage in the later laundering treatment.

In selecting the materials, however, for these plies, their coefficients of shrinkage are determined with substantial exactness, since it has been found that it is not sufficient to proceed with the mere knowledge that the outer

plies have a higher coefficient of shrinkage. A difference in the shrinkages of the inner and outer plies in excess of that required to bring the outer plies in flat tensioned contact with the inner ply, will result in wrinkling; and an insufficient difference between their shrinkages will not produce the desired result. Consequently, it has been found important to employ fabrics having almost exactly predetermined coefficients of shrinkage. These plies are superimposed with their edges substantially coincident and united by stitching 13 along or following the edges. The three plies of the top, when thus superimposed and united along their edges, are then turned to fold over the stitched-together edges, as indicated at 14, on Figures 3 and 4. The inturned edges and the bodies of the plies are then secured together by a line of stitching 15.

20 The top member is secured to a band of somewhat similar construction, and which is shown most clearly in Figures 6 and 7. The band comprises an interliner or stiffening ply 16, and outer wider plies 17, 18. As in the 25 top, the interliner 16 is preferably formed of material, such as commercially shrunk fabric, having a lower coefficient of shrinkage than the outer plies 17, 18 and materials are employed having almost exactly predetermined coefficients of shrinkage in order that the outer plies may, when shrunk, be suitably tensioned upon the inner play and shrunk into close contact therewith.

The bottom edge 19 of the ply 17 is folded 30 over the bottom edge of the band interliner or intermediate ply 16 to envelop the latter, and the two plies are united by a line of stitching 20. The band and top are united by interposing the top between the upper edges 35 21 of the outer band plies 17, 18, and the top and outer band plies in this overlapping relation are sewed together by two lines of stitching 22, 23, the former extending only through the inturned edges of the band plies 40 17, 18, and the latter being passed through all of the plies after the plies 17, 18 are moved from the position illustrated in Figure 5 to that of Figure 7. It will be observed that the band interliner 16 is sufficiently narrower than 45 the outer plies 17, 18, so that it does not overlap the edges of the top plies, its upper edge being thereby spaced downwardly from the top.

In Figure 5 the top and band are shown as united by the stitching 22, and in Figure 7, 50 the band plies 17, 18 are shown as folded downwardly to receive the stitching 23.

The band is then quilted (Fig. 8) by the stitching 24, thus uniting all the band plies intermediate their top and bottom edges, and 55 after the formation of the buttonhole 25, and the attachment of the button 26, the collar is ready for the shrinkage process. It will be noted that in this condition the band ply 18 has a raw bottom edge extending downwardly 60 a substantial distance beyond the folded edge

19 of the other outer ply, which envelopes the interliner. However, the three band plies are united by the stitching 23, 24, and the band and top being similarly formed of plies having different and predetermined coefficients of shrinkage, will similarly react to the shrinkage process.

When the entire collar has been completed, and is ready for attachment to the shirt, it is then subjected to a careful shrinking process, 70 the result of which is to cause the comparatively light and commercially unshrunk outer plies to shrink tightly upon the interposed heavier plies 10 and 16 of commercially shrunk fabric, and to a predetermined extent 75 because of the selection of fabrics whose shrinkage under this treatment has been substantially exactly predetermined. This operation tends not only to prevent or remove wrinkles from the outer plies and to cause the outer plies to closely embrace and to be tensioned upon the heavier interlining ply, but 80 also have a number of additional results.

The shape of the collar because of the use 85 of fabrics having predetermined coefficients of shrinkage, is maintained, and there is no distortion of the collar because of excessive shrinkage of outer plies upon the inner ply. Moreover, there is a shrinkage only sufficient to tension the outer plies properly upon the 90 interlining ply.

By the provision of a band similar in construction to the top, the desired relation between these parts is retained after the laundering treatment. As will be understood, the corresponding plies of the band and top, including the outer plies, are preferably made of the same fabrics or at least fabrics having the same predetermined coefficients of shrinkage to provide a uniform reaction to the process 100 and so that the effect of the shrinkage process will be substantially the same throughout the collar. In some instances the band interliner may be heavier than the top interliner but it should have the same coefficient 105 of shrinkage.

This shrinkage process to which the completed collar ready for attachment to the shirt is subjected, will vary with different fabrics, since it has been found necessary for various 110 reasons to exercise more care with certain fabrics, for instance, to prevent discoloration which would result in a collar and shirt unmatched in appearance.

The first step with collars of all fabrics is 115 to thoroughly wet the entire collar, which is then subjected to a drying operation. This wetting and drying operation which effects the shrinkage is preferably carried out in such a way as to leave the collars thereafter in flat or unmussed condition.

Collars of some fabrics will then be ready 120 for attachment to the shirt, but others which require more care may be subjected to a dampening, and thereafter to a seasoning period,

preferably of at least twelve hours. Following this seasoning, a preliminary ironing is given the collars, and they are then ready for attachment to the shirt.

5 In attaching the collar, the neck edge 27 of the shirt (Figure 9) is arranged in coincidence with the bottom edge 18' of the band 10 ply 18, with the bodies of the ply 18 and the body of the shirt material superimposed. A line of stitching 29 is then run through these 15 plies. The band ply 18 and the collar are then folded over the stitching 19 to carry the interliner 16 and other band ply 17 to the opposite side of the shirt neck to which the interliner and band ply 17 are attached by a 20 line of stitching 30. It will be observed that the folding of the edge 19 over the interliner provides a finished edge for final attachment to the shirt, and the greater width of the 25 ply 18 with its edge 18' positioned below the bottom of the edge of the ply 17, facilitates initial attachment of the ply 18 to one side of the shirt.

It will be understood, of course, that the 25 invention is not limited to the details of the method or collar construction set forth, since numerous variations may be made without departing from the invention which is defined by the following claims.

30 I claim:

1. That improvement in the art of making fold collars of the shirt-attached type, which consists in making the collar top and band, the latter comprising a plurality of plies, 35 uniting the top and band, subjecting the collar to a shrinkage process with the free edge of the band having the plies unsewed so that the band is open along said edge, and thereafter sewing the collar to the shirt.

40 2. That improvement in the art of making fold collars of the shirt-attached type, which consists in making a collar top and band, having substantially the same predetermined coefficients of shrinkage, the band having a 45 plurality of plies, uniting the top and band, subjecting the collar to a shrinkage process with the free edge of the band open, and thereafter sewing the collar to the shirt.

3. That improvement in the art of making 50 fold collars which consists in uniting a band and top, each consisting of at least three plies including an intermediate and two outside plies, the material of the inner ply and outer plies having different and substantially predetermined coefficients of shrinkage, with the outer plies having a relatively higher coefficient of shrinkage, and subjecting the collar to a shrinking process.

4. That improvement in the art of making 55 fold collars of the shirt-attached type, which consists in uniting a band and top, the latter consisting of at least three plies, including an intermediate and two outside plies, the material of the inner ply and outer plies having different and substantially exactly pre-

determined coefficients of shrinkage, with the outer plies having a relatively higher coefficient of shrinkage, subjecting the collar to a shrinking process, and then sewing the band to a shirt.

5. That improvement in the art of making fold collars of the shirt-attached type, which consists in uniting a band and top, each consisting of at least three plies including an intermediate and two outside plies, the material of the inner ply and outer plies having different and substantially predetermined coefficients of shrinkage, with the outer plies having a relatively higher coefficient of shrinkage, subjecting the collar to a shrinking process, and then sewing the band to a shirt.

6. That improvement in the art of making fold collars of the shirt-attached type, which consists in uniting a band and top, the latter consisting of at least three plies including an intermediate and two outside plies, the material of the inner ply and outer plies having different and substantially predetermined coefficients of shrinkage, with the outer plies having a relatively higher coefficient of shrinkage, subjecting the collar to a shrinking process, giving the collar a preliminary ironing and then sewing the same to a shirt.

7. A collar comprising a band of at least three plies, including an intermediate stiffening ply and two wider outer plies, the bottom edge of one outer ply being folded over the bottom edge of the inner ply to envelop the same, stitching securing the inner ply and said outer ply together adjacent said fold, a fold-over top sewed to said outer band plies in overlapping relation and adjacent the upper edges of the outer band plies independently of the inner band ply.

8. A collar comprising a band of at least three plies, including an intermediate stiffening ply and two wider outer plies, the bottom edge of one outer ply being folded over the bottom edge of the inner ply to envelop the same, stitching securing the inner ply and said outer ply together adjacent said fold, a fold-over top sewed to said outer band plies in overlapping relation and adjacent the upper edges of the outer band plies independently of the inner band ply, said inner ply having its upper edge spaced downwardly from the overlapping edges of the outer band plies and the top.

9. That improvement in the art of making collars of the shirt-attached type, which consists in forming a band of at least three plies, including an intermediate stiffening ply and two wider outer plies, folding the bottom edge of one outer ply over the inner ply to envelop the same, sewing the inner ply and said outer ply together adjacent said fold, forming a fold-over top, and sewing the same to said outer band plies in overlap-

ping relation and adjacent the upper edges of the outer band plies without overlapping the inner band ply, subjecting the collar to a shrinking process, and then sewing the same to a shirt.

10. That improvement in the art of making collars of the shirt-attached type, which consists in forming a band of at least three plies, including an intermediate stiffening 10 ply and two wider outer plies having substantially coinciding edges, folding the bottom edge of one outer ply over the inner ply to envelop the same, sewing the inner ply and said outer ply together adjacent said 15 fold, forming a fold-over top, and sewing the same to said outer band plies in overlapping relation and adjacent the upper edges of the outer band plies without overlapping the inner band ply, said intermediate ply 20 having its upper edge spaced downwardly from the overlapping edges of the outer band plies and the top, subjecting the collar to a shrinking process, and then sewing the same to a shirt.

25 11. A laundered collar of the shirt-attached type comprising a fold-over top of multi-ply formation and a band having at least three plies, one an intermediate narrower 30 ply, the other plies having substantially co- incident edges, the fold-over top having one edge interposed between the outer band plies without overlapping the intermediate band 35 ply, one of the outer band plies having its bottom edge folded over the edge of the inner 40 ply and secured thereto, the material of said band plies and the plies of the top having substantially predetermined coefficients of shrinkage, the coefficients of shrinkage of the outer band plies and of the top ply of the 45 fold-over top being higher than the shrinkage coefficients of the remaining plies.

12. That improvement in the art of making fold collars of the shirt-attached type, which consists in forming a band and a top, 45 each having at least three plies, one an inner stiffening ply, and the others outer plies, the outer plies having higher coefficients of shrinkage than the inner ply, uniting all the 50 superimposed plies of the top and band and sewing together the top and band, subjecting the collar to a shrinking process whereby the outer plies are tensioned by their relatively greater shrinkage upon their respective inner plies, and then sewing the collar to a shirt.

55 13. That improvement in the art of making fold collars of the shirt-attached type, which consists in making the collar top and band, the latter comprising a plurality of 60 plies, uniting the top and band, subjecting the collar while in a substantially flat condition to a shrinkage process with the free edge of the band having the plies unsewed so that the band is open along said edge, the shrink- 65 age process involving wetting and drying of

the collar and thereafter sewing the collar to the shirt.

14. That improvement in the art of making fold collars of the shirt-attached type, which consists in making the collar top and 70 band, the latter comprising a plurality of plies, uniting the top and band, subjecting the collar to a shrinkage process with the free edge of the band having the plies unsewed so that the band is open along said edge, said shrinkage process comprising (a) wetting and drying of the collar, and (b) dampening and aging, and thereafter sewing the collar to the shirt.

15. That improvement in the art of making fold collars of the shirt-attached type, which consists in making the collar top and 75 band, the latter comprising a plurality of plies, uniting the top and band, subjecting the collar to a shrinkage process with the free edge of the band having the plies unsewed so that the band is open along said edge, said shrinkage process comprising (a) wetting and drying of the collar, (b) dampening and aging, and (c) a preliminary ironing, and 80 thereafter sewing the collar to the shirt.

In testimony whereof I have hereunto set my hand.

RALPH HUNTER.
